CREEPING TOY

Otto Steinitz, New York, N. Y.

Application November 30, 1945, Serial No. 631,825

5 Claims. (Cl. 46—123)

1

My invention relates to creeping toys, for example to toys simulating a turtle or another creeping animal.

Objects of my invention are creeping toys moving horizontally in a funny, surprising, realistic and apparently spontaneous manner, toys creeping over the ground or a substantially horizontal surface by sliding movement of their feet or supporting bases without rolling or walking, that is without temporarily lifting their feet from the ground, and toys having lower surfaces slidingly contacting the ground without denting, scratching or grooving the same.

Other objects are to operate these toys without clockworks, springs or any other artificial power source, to operate these toys by a vertically directed manual or outer force which, apparently, does not drive the toy in the moving direction, and, thereby, to make the horizontal movement of the toy appear spontaneous, surprising and amusing.

Further objects are a manually operated creeping toy which moves in one definite forward direction without any apparent means pushing or pulling the toy in this particular direction or preventing the toy from moving in the opposite or in any other direction, and thereby to make the movement of the toy still more surprising and amusing.

Still other objects are a creeping toy which is operated by a simple hand movement requiring no skill, no appreciable effort and, while substantially vertical, no accurate direction, nor requiring the combination of simultaneous movements in several directions, and to make this operation easy and adapted for a little child.

Still further objects are a creeping toy of utmost simplicity of structure, to make, by this very simplicity, the movement of the toy still more surprising and amusing, and to provide for simple, inexpensive and quick manufacture of the toy.

Still other objects and advantages will appear from the following description, from the appended claims and from the accompanying drawing showing an exemplifying embodiment of the invention.

In order to attain these objects, I use a structure resting on two bases or sets of feet which are freely slidable on any substantially horizontal ground and are movable relatively to each other to and fro in a substantially horizontal direction. These bases have lower surfaces which are sufficiently large and smooth or even to support the structure without denting or substantially enter-

2

ing the ground whereby the toy can be slidably shifted in all directions without scratching the supporting ground surface and without any other resistance than the friction between the bases and the ground. According to an essential feature of the invention, the friction of one base is made different from that of the other base. This can be made by providing the bases with surfaces of different frictional coefficients, or, preferably, by loading the bases differently, or by both. When the bases are moved relatively to each other, the sliding tendency of the base having the larger friction is suppressed and this base remains stationary while the other base slides over the ground in the same direction as this movable base moves relatively to the stationary base.

In inoperative condition of the toy or when no manual force is exerted, the loads of the bases are determined by the toy's weight and its distribution over the bases. This distribution is determined by the ratio between the respective distances of the bases from the vertical line through the toy's center of gravity or, in other words, by the horizontal distances of the bases from this center.

According to another feature of the invention, the loads are modified, that is increased or reduced, during the operation of the toy by a vertical outer or manual force which simultaneously causes the horizontal relative movement of the two bases and which acts along a vertical line having a distance from the toy's center of gravity whereby this force is distributed over the two bases differently from the distribution of the toy's weight. This force and the mentioned distances are so directed and measured that, during the relative movement of the bases in one direction, one base has the larger load or friction and that, during the reverse relative movement, the other base has the larger load or friction.

Due to this reversal of the load or frictional relationship, the stationary and the slidable bases exchange roles whenever the relative movement is reversed whereby the two bases move alternatingly in the same direction relative to the ground. This mechanical trick or principle makes it possible to attain the objects of the invention in a surprisingly impressive and simple manner, for example, by the embodiment shown in the drawing in which:

Fig. 1 shows a front view of this illustrative embodiment.

Fig. 2 shows a longitudinal cross-section taken along the line 2—2 in Fig. 3.

Fig. 3 shows a view of the same embodiment seen from the lower side.

Fig. 4 shows a schematically simplified side view of the same embodiment, adapted for explanation of certain force and measure relations.

Referring to the drawing, numeral 1 designates a body comprising an upper plate or back 2 which may be round and may have a convex upper surface simulating the back of an animal, and two feet 3 affixed to the plate 2. The feet 3 have even, lower surfaces contacting the ground and forming together a weight supporting base 4 of the toy. Another body 5 comprises a beam or narrow plate 6 positioned under the plate 2 and two feet 7 affixed to the beam 6. The feet 7 have even, lower surfaces contacting the ground and forming together the other base 8 of the toy.

The bodies 1 and 5 are guided relatively to each other in a substantially horizontal direction by any suitable means. Preferably, both bodies are hinged to two arms or connecting members 9 and 10. Hinge axles 11 and 12 may be carried by lobes or projections 13 extending from the lower side of the plate 2. Hinge axles 14 and 15 may be carried by extensions 16 of the beam 6. The member 9 has bores for the passage of the hinge axles 11 and 14. The member 10 has bores for the passage of the hinge axles 12 and 15. The member 9 may have a front extension 17 simulating the head of an animal, and the member 10 may have a rear extension 18 simulating the tail of the animal. Preferably, the longitudinal distance between the axles 11 and 12 equals about the distance between the axles 14 and 15, and the vertical distance between the axles 11 and 14 equals about the distance between the axles 12 and 15 whereby the bodies 1 and 5 and the connecting members 9 and 10 form a movable system hinged at the corners of a parallelogram, and the bodies 1 and 5 or the bases 4 and 8 can move to and fro parallel to each other in a substantially horizontal direction, without any substantial resistance, as far as the structure permits, end stops for this movement being formed by the contact of one or both of the members 9 and 10 with one of the bodies, for example with the plate 2.

A substantially vertically extending member 19 is attached to a vertically movable point of this system, for example to a point of the head extension 17 of the connecting member 9. The member 19 can be moved in vertical direction by a manual force which may act on the upper end of the member 19. Instead or in addition, another vertically extending member 20 may be attached to another vertically movable point, for example to the tail extension 18 of the connecting member 10. Each of the members 19 and 20 may be a cord or a similar flexible element adapted to be pulled or may be a rod or similar stiff element adapted to be pulled or pushed.

The vertical extension or direction of the members 19 and 20 permits operation of the toy without pushing or pulling the same in the creeping or horizontal direction, and has the additional advantage that the toy can be conveniently operated by an upright person. Preferably, the members 19 and 20 are sufficiently long to reach from the toy positioned on the ground to the hands of such a person. In the drawing, the members 19 and 20 are represented broken off for the sake of space economy.

The parts of the toy are so arranged and weighted that the center of gravity 21 of the

toy is located in a vertical line positioned between the bases 4 and 8 or at least between the outer edges of these bases. Preferably, the center of gravity 21 is considerably nearer to one of the bases, for example to the front base 8 whereby this latter base is considerably heavier weighted than the other base. The distribution of the toy's weight over the two bases is not absolutely constant, a slight modification of this distribution resulting from the relative movement of the bodies 1 and 5 which movement shifts the one or the other of the bases in the same direction, but in a lesser degree than the center of gravity. This slight modification of weight distribution can be neglected in the description of the toy's operation.

Each base is sufficiently broad, or the feet forming the base are sufficiently spread laterally, and the two bases have a sufficient longitudinal distance for the two bases to form together or to define an area supporting the toy stably under all conditions.

The movable system may be so weighted or may have a vertically movable part which is so heavy that the gravity tends to move the system into one of its extreme positions. Preferably, the head 17 is made sufficiently heavy to move, by its weight, the bodies into the relative position shown in Fig. 2 in full lines whereby the bodies make their relative movement in one of the two opposite directions automatically. The heavy head 17, in addition, facilitates the proper location of the toy's center of gravity which, if one of the movements is automatic, must be nearer to the base 8 or to that base which is to be stationary during the automatic movement. The reverse relative movement may be effected in this case either by pulling the member 19 which may be flexible or stiff or by pushing a stiff member 20 down. If movement in one direction is automatic, only one of the members 19 and 20 is necessary and the other member may be omitted.

The movable system is so designed that the base 8 has a larger load or friction than the base 4 when the relative movement urges the base 4 in forward direction, and that this relationship between the two bases is reversed when the reverse relative movement urges the base 8 in forward direction. This is a structural feature residing in definite and particular relations between measures of parts of the movable system as will be shown in the following.

Fig. 4 shows the movable system schematically and in that position where the parallelogram is rectangular. The small deviations from this position which occur during the relative movements are neglected in the following calculation for the sake of simplification and clearer explanation. The arrow Q indicates the total weight of the toy. A and B indicate the loads of the bases 8 and 4 respectively, W the weight of the head 17, and H the manual force operating the member 19. The arrows Q, A and B point in that direction in which the respective forces act with respect to the toy. The horizontal distances of the bases from the toy's center of gravity 21 or the distances of A and B from Q are a and b respectively. The horizontal distance of the member 19 or of the force H from A or the base 8 is c . The vertical distance between the hinges 11 and 14 is d . The horizontal distance of H or of the member 19 from these hinges is h . The horizontal distance of W from these hinges is w .

Q, W, H, a, b, c, d, h and w may have various

values, provided that these values suffice certain conditions or stand in certain relationships as will appear from the following calculations. For example, the following values measured in any unit of length, are chosen: $a=3$; $b=7$; $c=6$; $d=3$; $h=6$; $w=5$. By known scientific method, it can be deduced that

$$A = Q \frac{b}{a+b} - H \frac{a+b+c}{a+b} \quad (1)$$

and

$$B = Q \frac{a}{a+b} + H \frac{c}{a+b} \quad (2)$$

The base 4 is farther from A than the base 8, that is b is larger than a . It results that, when H is zero, that is when no manual force is exerted, B is smaller than A and equal to

$$Q \times \frac{a}{a+b} \quad (3)$$

The required tendency to move automatically by gravity defines a relationship which, for the illustrative embodiment shown, can be deduced from Fig. 4. Obviously, the product Ww must be larger than the product fBd (where f is the coefficient of friction). Inserting the value (3) for B, we find that W/Q must be larger than

$$f \times \frac{a}{a+b} \times \frac{d}{w}$$

Inserting the chosen values for a , b , d and w , we find that, in the exemplifying embodiment, W/Q must be larger than $0.18 f$. In this embodiment, the weight of the head 17, W , is 24 per cent of the toy's total weight Q , that is W/Q equals 0.24 whereby this condition is fulfilled for friction coefficients f ranging between zero and 1.3, that is for all practical purposes. The chosen value of W provides for an excess of moving force which is larger or smaller, depending on the actual value of f . This excess is consumed for more or less quick acceleration of the automatic movement.

The statement that the manual force H makes the load B larger than the load A or reverses the positive sign of $(A-B)$ into the negative, defines a relationship between the values a , b and c . From the Equations 1 and 2 follows that

$$A-B = Q \frac{b-a}{a+b} - H \frac{a+b+2c}{a+b}$$

If H is zero, $(A-B)$ is obviously positive, b being larger than a . $(A-B)$ becomes negative if $H \times (a+b+2c)$ is larger than $Q \times (b-a)$ or if

$$H/Q > \frac{b-a}{a+b+2c}$$

The measures a , b and c are so chosen that this condition is fulfilled. The value H/Q can be determined in the following way:

Obviously, the force H is just as large as necessary to overcome the weight of the head W and the ground friction A of the base 8 when the manual force turns the connecting member 9 around the hinge axle 11. The very small additional resistances, for example the friction of the hinges, can be neglected. It results that the product Hh is equal to the sum of the products Ww and fAd . After inserting the value from the formula (1) for A and some transformation, we find:

$$H/Q = \frac{w(a+b)W/Q + bdf}{(a+b)h + (a+b+c)fd}$$

or, with the chosen values of W/Q , a , b , c , d , h and w :

$$H/Q = \frac{12+21f}{60+48f}$$

Assuming that f varies between zero and 1.3, H/Q varies between 0.2 and 0.321. Additional resistances, due to hinge friction and so on, may make H/Q a little larger. In any case, H/Q is larger than $(b-a)/(a+b+2c)$ or 0.1818 whereby the condition for reversal of the sign of $(A-B)$ or of the load relationship between the two bases is fulfilled.

The above given values of a , b and c fulfill also the further condition that the load A remains positive and that, consequently, the base is not lifted from the ground, but moves sliding over the same. The equation (1) shows that A is positive if

20

$$Q \frac{b}{a+b}$$

is larger than

$$H \frac{a+b+c}{a+b}$$

25

or H/Q is smaller than

$$\frac{b}{a+b+c}$$

30 for the chosen values of a , b and c ,

$$\frac{b}{a+b+c} \text{ equals } 0.4375$$

For the entire range of f , H/Q is smaller than this latter value.

When the manual force is exerted, A is reduced from 0.7 Q to a value between 0.38 and 0.186 Q , and B is increased from 0.3 Q to a value between 0.42 and 0.493 Q . Both loads A and B remain positive, but their difference changes from positive into negative.

When the movable system is moved by the manual force, the base 4 is converted into that base which has the larger load and friction and, therefore, stands still while the base 8 and the body 5 slide forward from the position shown in full lines into the position shown in dotted lines in Fig. 2. At the same time, the head 17 and the tail 18 move from the positions shown in full lines into that shown in dotted lines in the same figure. Then, the member 19 is relaxed whereupon the head 17 drops and, by its weight, moves the bodies 1 and 5 relatively to each other in the opposite direction. At this time, the base 8 has the larger load and friction and stands still while the base 4 and the body 1 slide forward relatively to the ground. Then the pull on the member 19 is repeated whereby the base 8 makes another step, and so on, alternating pulling and relaxing of the member 19 resulting in alternating sliding steps of the two bodies in the same forward direction relatively to the ground.

During each of these steps, the momentarily sliding base, being less loaded than the momentarily stationary base, moves against a frictional resistance much smaller than that resistance which would correspond to half the weight of the toy. This has the additional advantage that the force necessary for moving the toy is relatively small and that the toy can easily creep over a ground of relatively high friction.

If the head is not sufficiently heavy or if the two bodies do not move automatically in one of the two relative directions, alternative movement 75 in these two directions may be effected by one

stiff member 19 or 20 which is alternately pushed and pulled vertically, or may be effected by alternating use of both members 19 and 20. In the latter case, both members are preferably pulled and may be flexible. In each of these cases of operation, a reversal of load relationship corresponding to the inventive principle results from the same manual force which simultaneously causes a reversal of the relative movement of the two bodies and a reversal of that direction in which these bodies are urged to slide relatively to the ground, provided that the distances of the bases 4 and 8 and of the operated members 19 and/or 20 from the vertical line through the center of gravity 21 are suitably measured.

Suitable values of these distances can be determined for any case of operation, whether one or two members 19 or 20 are used and whether they are pulled or pushed, by a calculation corresponding to that given above for one of these cases of operation, or can be found by experiment. Properly measured, these distances fulfill the requirements of which this calculation is the mathematical deduction or expression. With other words, these distances are so measured that the respective manual force makes that base which is simultaneously urged in forward direction less loaded than the other base.

The exemplifying calculation given previously assumes that both bases have the same co-efficient of friction. If the bases have different co-efficients of friction, for example if the ground contacting surface of one base is made rougher than that of the other base, the structural conditions and the corresponding calculations have to be slightly modified. In this case, instead of the sign of $(A-B)$, the sign of $(Af'-Bf'')$, where f' is the co-efficient of friction of the base 8 and f'' that of the base 4, decides which of the bases is stationary and which is slidable relatively to the ground. The horizontal distances of the bases 8 and 4 and of the members 19 and 20 from the center of gravity 21 are so measured that the manual force makes the friction resulting from the load and from the co-efficient of friction smaller on that base which is simultaneously urged forward than on the other base.

This relationship of measures can be expressed in mathematical form by the same method as has been used before. Under consideration of the different co-efficients of friction, the results are modified. For example, the base 8 is stationary and the base 4 is slidable when H is zero if $(b \times f')$ is made larger than $(a \times f'')$ or if b/a is made larger than f''/f' . In this case b is not necessarily larger than a . The force H reverses the sign of $(Af'-Bf'')$ if

$$\frac{bf' - af''}{af' + bf' + c(f' + f'')}$$

is smaller than H/Q , this latter value being determined in the same manner as in the previous calculation.

I desire it understood that my invention is not confined to the particular embodiment shown and described, the same being merely illustrative, and that the invention may be carried out in other ways without departing from the spirit of my invention, as it is obvious that the particular embodiment shown and described is only one of the many that may be employed to attain the objects of my invention.

I claim:

1. A creeping toy comprising a movable system comprising two bodies guided relatively to each

other in a substantially horizontal direction, each of said bodies having a base slidably contacting the ground, said bases forming a stable support of the toy, and means to move said bodies to and fro relatively to each other whereby each of said bases is urged in a direction opposite to that in which the other base is urged simultaneously and is urged alternately forward and backward relatively to the ground, said means comprising a vertically extending member connected to said system at the same side from the toy's center of gravity as one of said bases, said member being operated by a vertical manual force and moving said bodies relatively to each other, the horizontal distances of said member and of said bases from said center being so directed and measured that said force makes that base which is being urged forward less loaded than the other base.

2. A creeping toy comprising a movable system comprising two bodies guided relatively to each other forward and backward in a substantially horizontal direction, each of said bodies having a base slidably contacting the ground, said bases having opposite directed and differently measured horizontal distances from the toy's center of gravity whereby the base having the smaller distance is more loaded than the other base, said system having a vertically movable weight having its lowest position when the less loaded base is in its most forward position, and being sufficiently heavy to move said system automatically into said forward position; and a vertically extending member connected to said system at the same side from the toy's center of gravity as one of said bases, operated by a vertical manual force and moving said system in a direction opposite to said automatic movement, the horizontal distances of said member and of said bases from said center being so directed and measured that said force makes that base which has the smaller distance from said center less loaded than the other base while said force is being exerted.

3. A creeping toy comprising a movable system comprising two bodies guided relatively to each other in a substantially horizontal direction, each of said bodies having a base slidably contacting the ground, said bases having opposite directed distances from the toy's center of gravity; and two vertically extending members connected to said system, operated by vertically upward directed manual force and moving said bodies in opposite relative directions, one of said members being positioned at the same side from said center as one of said bases, and the other member being positioned at the same side as the other base whereby alternating operation of said members alternately makes one base less loaded than the other base.

4. A creeping toy comprising a movable system comprising two bodies, each having two hinges positioned at substantially the same height over the ground, and two arms, one connecting one hinge of one of said bodies to one hinge of the other body and the other arm connecting the two other hinges, each of said bodies having a base slidably contacting the ground, said bases forming a stable support of the toy; and means moving said system to and fro whereby said bodies are moved relatively to each other in a substantially horizontal direction and said bases are urged in opposite directions and, alternately, forward and backward, said means comprising a vertically extending member connected to one of said arms, operated by vertical manual force and moving said system, the horizontal distances of

said member and of said bases from the toy's center of gravity being so directed and measured that said force makes that base which is urged forward less loaded than the other base.

5. A creeping toy comprising a movable system comprising two bodies guided relatively to each other in a substantially horizontal direction, each of said bodies having a base slidably contacting the ground, said bases forming a stable support of the toy and having different co-efficients of friction; and means moving said bodies to and fro relatively to each other whereby each base is urged in a direction opposite to that in which the other base is simultaneously urged, and is

urged alternately forward and backward relatively to the ground, said means comprising a vertically extending member connected to said system at the same side from the toy's center of gravity as one of said bases, said member being operated by a vertical manual force and moving said bodies relatively to each other, the horizontal distances of said member and of said bases from said center being so directed and measured that said force makes the friction resulting from load and coefficient of friction smaller on that base which is urged forward than the friction on the other base.

OTTO STEINITZ.
